SOLENOID OPERATED POSITIVE CLUTCH

Werner M. Lowenstein, New York, N. Y.; now by
change of name Warren M. Lowry

Application March 3, 1950, Serial No. 147,358

1 Claim. (Cl. 192—84)

1

This invention relates to the remote control of fluid control valves, such as valves in a fuel line leading to an oil truck filling station in a yard. It requires the cooperation of an automatic control or a person in control in the yard office with the driver of the truck to operate the fluid dispensing valve, assuring that only the authorized volume of fluid can pass the valve.

According to the present invention, the valve-operating handle is normally disengaged from the valve-operating shaft so that positioning this handle in its operative position by the driver of the truck or another unauthorized person will not cause rotation of the valve-operating shaft and opening of the fluid-control valve. A signal from the office is required to engage the handle to the valve-operating shaft so that fluid can be dispensed by operation of the shaft. Discontinuance of the signal will cause the shaft to become disengaged, stopping the flow of fluid.

Since the rate of fluid flow is known, the time interval elapsed between opening and closing of the valve is a measure of the amount of fluid traversing the valve during the loading operation.

It is a further feature of the present invention that the cooperation required from the office can be supplied by an automatic switching mechanism. If it is desired to dispense a predetermined amount, the switching mechanism is preset to close the valve after the specified time interval.

It is an advantage of the present invention that the fluid flow can be controlled independently of the operator in a simple and effective manner. A further advantage is that this control can be effected automatically.

Other advantages will become apparent in conjunction with the following specification and drawings in which:

Fig. 1 is a sectional view of a valve control mechanism according to this invention with the valve-operating shaft disengaged from the handle;

Fig. 2 is a side view, partly in section, of the valve control mechanism shown in Fig. 1 with the valve-operating shaft engaged to the handle; and

Fig. 3 is a front view of the valve control mechanism, showing the handle in its valve-opening and valve-closing positions.

Referring to Figs. 1 and 2, the valve control mechanism is contained in a valve housing 1, provided with a cover 2, which cover is connected to the housing by threading at 3. The housing

2

1 is provided with the operating handle 13 and with guiding apertures 5 for locking pins 4, which are screwed to a support 6, carried by the solenoid core 7 of solenoid 8. Screws 10 connect the solenoid to the housing 1. The valve-operating shaft 9 is provided with a locking plate 11, having tapered apertures 12, aligned with the apertures 5 in the housing 1 in their normal positions.

10 The solenoid 8 is supplied with current through wires 14 and 15 from power supply 16. The switch 17 is preferably located at the control station, for instance in the yard office. This switch is either manually operated and the time 15 interval between closing and opening of the switch is noted or an automatic switching mechanism is provided. The automatic switching mechanism may be controlled by punched cards, the position of the hole or holes in the card depending on the amount of fluid it is intended to dispense so that the card will cause the switch 17 to open after a predetermined interval of time corresponding to the amount of fluid.

It will be seen that if the locking pins 4 are 25 in the position shown in Fig. 1, rotation of handle 13 will cause rotation of the housing assembly containing the solenoid 8 and the locking pins 4 around the cylindrical extension 18 of the locking plate 11. The annular shoulder, formed 30 by the disc 19 which is held in place by the screw 20, provides an abutment for the rotating housing 1. The spring 21 forces the solenoid core 7 away from the housing 1, thereby maintaining locking pins 4 in their disengaged position which 35 is illustrated in Fig. 1.

If the switch 17 is closed and current is supplied to the solenoid wires 14 and 15, the core 7 will move downwards, compressing spring 21, until the stop 22 of the core rests on the solenoid casing. The support 6, carrying locking pins 4, will move with the core 7 towards the housing 1, thereby engaging locking pins 4 in apertures 12 of the locking plate 11.

In Fig. 3 is shown the mounting of the locking device on the housing 23 of the valve. Ports 24 for the entry and exit of the fluid into and out of the pipe housing 23 are provided. The cover 2 of the valve actuating mechanism is shown mounted on the valve housing 23. It carries the 45 valve actuating handle, illustrated in position 13, when the valve is closed, and in position 13A, when the valve is open.

In operation, when it is intended to dispense a predetermined amount of fluid, the truck to be filled will be moved in position, the switch 17

in the yard office will be closed either manually or by an automatic device and the equipment will be ready for operation. If handle 13 is now rotated, the pins 4 will transmit the rotating movement to the locking plate 11 to which the valve operating shaft 9 is connected so that fluid will start to flow.

The valve operating shaft is spring loaded, not shown, to assume a position in which the valve is closed. Hence, the valve will be closed in its normal position, and will be opened only if the valve operating shaft is engaged to the handle by means of the locking pins 4 and the handle is rotated to its operative position. This can be accomplished only if the locking pins 4 are in their engaging position, as shown in Fig. 2, and the handle 13 has been rotated to open the valve. Either rotation of the handle to the closing position or release of the locking member 11 from the locking pins 4, by opening of the switch 17, will thus operate to close the valve, shutting off the fluid flow.

When the predetermined amount of fluid has been dispensed, the operator will return the handle 13 to the closing position. However, to prevent excess flow of fluid in case the operator omits to return the handle 13, the switch 17 will be opened, releasing the core 7 and thereby retracting locking pins 12 from locking plate 11. This will assure that only the intended volume of fluid has been permitted to pass through the valve.

By controlling the instant of fluid admission through the valve and the instant of termination of fluid flow, the time interval during which the fluid has been dispensed can be controlled. Since the rate of flow of the fluid is known, the amount of fluid passing the valve each time it is opened and subsequently closed is thus available and controllable from the office, permitting a close check on the dispensing operation. If an automatic control is provided for the switch 17, the control is preset for the volume it is intended to dispense so that the valve will close after the desired volume has passed therethrough.

The structural details shown and described may vary within wide limits without deviating

from the spirit of the present invention, and it is desired that the appended claims be construed in their broadest sense.

Having thus described my invention, what I claim and desire to secure by Letters Patent is as follows:

A locking device comprising a disc member having tapered apertures therein secured to a shaft adapted to be rotated, a housing member having a flat bottom with a handle thereon disposed adjacent said disc member in face to face relationship, said housing having a plurality of pin receiving apertures in its base superimposable over said tapered apertures of said disc member, a plurality of solenoid pins disposed in said housing apertures for reciprocal movement into and out of said disc member apertures, a support member fixed to said pins, a spring for urging said support member continuously away from said disc member, a solenoid having a movable core secured to said support member, and electrical means for energizing said solenoid, whereby movement of said solenoid core downward compresses said spring and effects insertion of said solenoid pins into said disc apertures, thereby locking said handle containing housing member to said shaft.
